UNITED STATES PATENT OFFICE.

JOSHUA THOMAS, OF JOLIET, ILLINOIS.

CURTAIN BRACKET.

Application filed September 24, 1923. Serial No. 664,539.

This invention relates to curtain brackets, and an object of the invention is to provide a bracket structure which may be used at both ends of a curtain or shade roller and 5 also one which is designed to support both the window shade and drapes, curtains or the like.

Another object of this invention is to provide a bracket as specified which is comparatively simple in construction and may be constructed at a comparatively low cost, and one which includes a screw extension in its construction to facilitate and permit its attachment to the window frame.

15 Other objects of the invention will appear in the following detailed description taken in connection with the accompanying drawing wherein:

Fig. 1 is a side elevation of the improved 20 bracket.

Fig. 2 is a side elevation of the bracket showing the side opposite to that disclosed in Fig. 1.

Fig. 3 is a plan view of the bracket.

25 Fig. 4 is a detail section on the line 4—4 of Fig. 3.

Referring more particularly to the drawings, the improved shade bracket comprises a main body 1 which is constructed of sheet 30 metal or analogous material and includes a relatively large side plate 2 which projects outwardly beyond the extension 3. The extension 3 is parallel to the extension 2 and is formed integrally therewith, as clearly 35 shown in Fig. 3 of the drawing. The extension 2 is provided with a relatively large opening 4 adjacent its outer end which is adapted to receive the supporting pole of drapes, lace curtains or the like, and which is 40 provided with a second opening 5 inwardly of the opening 4 which also can be utilized for supporting the rod or pole if it is desired to hang both curtains and drapes. A relatively small opening 6 is formed in the 45 side plate 2 and is adapted to receive the round trunnion on the end of a shade roller of the conventional spring type. The opening 6 aligns with the diagonal slot 7 which is formed in the outer end of the bracket 50 side plate 3. The slot 7 is adapted to receive the spring trunnion of a shade roller. The side plates 2 and 3 are held in spaced relation, one from the other by the eye 8 of a screw eye 9. The threaded shank of the 55 screw eye 9 extends through the connecting portion 10 of the bracket 1, which portion

connects the plates 2 and 3. The screw eye 9 is held against movement and securely connected to the bracket 1 by means of a rivet 11 which extends through the eye 8 and has 60 its ends upset in the usual manner, as clearly shown in Fig. 4 of the drawings.

In use, it will be seen, that only one type of bracket need be made it being unnecessary to make a pair of brackets for each window 65 structure as the improved bracket may be turned with the short side 3 inwardly at one side of the window so that the slot 7 may receive the spring trunnion and with the long side plate 2 inwardly at the opposite 70 side of the window so that the round trunnion on the roller may be received in the opening 6. It is understood that the screw eye 9 will be held against oscillatory movement both by means of the rivet 11 and by 75 the opening 12 through which the shank of the screw eye extends.

It is, of course, to be understood that the invention may be constructed in other manners and the parts associated in different relations and, therefore, I do not desire to be limited in any manner except as set forth in the claims hereunto appended.

Having thus described my invention what 80 I claim is:

1. A reversible supporting bracket comprising a U-shaped body having one side larger than the other and the larger side having its outer end reduced in size and provided with an opening, said larger side 90 having spaced openings formed in the intermediate portion thereof of different sizes, the smaller side having an oblique slot therein adjacent its outer end and aligning with one of the spaced openings in the larger side, a retaining screw having an eye disposed between the said plates with the shank thereof projecting thru the opening in the transverse portion, and a tubular rivet extending thru the sides of the body and the eye of the screw member for retaining said screw member in position with respect to the sides.

2. A bracket of the class described including a substantially U-shaped body defining side limb portions of different lengths, the longer of the limb portions defining an opening contiguous its outer end portion and a second opening inwardly and of a diameter smaller than the diameter of the first mentioned opening and a third opening inwardly and of a diameter smaller than the second mentioned opening, the shorter of the

limb portions having an outer end portion defining an oblique slot in alignment with the third mentioned opening, there being an opening formed in the bight portion defined by the body for the passage of the shank portion of a securing element, and a member having operative connection with the securing element and connecting the limb portions together, said member being disposed outwardly from the bight portion and functioning to properly space the limb portions together.

3. In combination, a body defining oppo-

site limb portions of different lengths, the longer of the limb portions defining a plurality of openings of different diameters, the shorter of the limb portions defining an oblique slot disposed in alignment with one of the openings, a member connecting the limb portions together and functioning to retain the limb portions in spaced relation, and a securing element operatively connected with the member.

In testimony whereof I affix my signature.

JOSHUA THOMAS.
